[57] CLAIM

The ornamental design for a anti-siphon valve body, as shown and described.

DESCRIPTION

FIG. 1 is a perspective view of an anti-siphon valve body embodying our new ornamental design and showing a solenoid actuator in broken line, the latter forming no part of the claimed design;

FIG. 2 is a front elevational view thereof, it being understood that the rear elevational view is identical as the front view, only reversed in orientation;

FIG. 3 is a top plan view thereof;

FIG. 4 is a bottom plan view thereof;

FIG. 5 is an end elevational view thereof, as seen from the left side of FIG. 1; and,

FIG. 6 is an end elevational view thereof, as seen from the right side of FIG. 1.
